Stephen C. Jones

Inventor:
Roy C. Jones,
by Chamberlin, Bremerton, W. Va.

UNITED STATES PATENT OFFICE.

ROY C. JONES, OF CHICAGO, ILLINOIS.

LOCKING HAIR-FASTENER.

1,385,349.

Specification of Letters Patent. Patented July 19, 1921.

Application filed May 2, 1921. Serial No. 466,104.

To all whom it may concern:

Be it known that I, ROY C. JONES, a citizen of the United States, residing at Chicago, county of Cook, State of Illinois, have invented a certain new and useful Improvement in Locking Hair-Fasteners, and declare the following to be a full, clear, and exact description of the same, such as will enable others skilled in the art to which it pertains to make and use the same, reference being had to the accompanying drawings, which form a part of this specification.

My invention has for its object to produce a simple and novel construction and arrangement by means of which two prongs of a hair pin or other hair fastener may, in effect, be conveniently and positively connected or locked together at their points or free ends after insertion into the hair; so as not only to lock the fastener into the hair and prevent it from accidentally dropping out but at the same time causing the fastener to act as a tie or binding means for a thick lock or strand of hair or for several overlying locks or strands or portion of a coil or braid.

In accordance with my invention I form one of the two prongs with a passage extending lengthwise through the same, one end of the passage opening out of the top or base of the fastener and the other end opening out of the prong near the point or free end thereof through the side facing the other prong, the passage thus being bent or deflected laterally near its lower end. In the other prong I place an opening, which may take the form of an eye, at a point on the inner side lying approximately in a continuation of the long axis of the laterally-extending portion of the passage. I also provide a thin resilient wire having on one end a head, this wire being completely withdrawn when the fastener is placed in the hair and being then pushed down into the passage until its inner end merges from the prong near the point thereof and passes laterally across the space between the prongs and into the opening in the second prong where it forms the interlock with the latter. The wire is preferably provided with a head and is made of just the right length to form the interlock when the wire is pushed in as far as the head will permit.

The various features of novelty whereby my invention is characterized will herein-after be pointed out with particularity in

the claims; but, for a full understanding of my invention and of its objects and advantages, reference may be had to the following detailed description taken in connection with the accompanying drawing, wherein:

Figure 1 is a view partly in elevation and partly in section of a hair pin arranged in accordance with the present invention;

Fig. 2 is a top plan or edge view of the hair pin; and

Fig. 3 is a view of the locking wire detached from the hair pin.

Referring to the drawing, 1 and 2 represent the two prongs of a hair pin pointed at their one end as indicated at 3 and connected together at their bases or other ends by a connecting piece, 4. The prong, 1, is bent laterally as indicated at 5 toward the prong, 2, near the free end or point. A passage extending lengthwise through the upper portion of the prong 1 and the bend 5 may conveniently be obtained by making at least this prong out of a small tube. An inlet end for the passage is obtained by punching or drilling a hole, 6, through the wall of the tube at the base of the prong, while an outlet from the passage is secured by forming a hole, 7, in the wall of the prong on the inner side thereof at the extreme inner end of the bend. In the prong 2, opposite the outlet 7, is a hole, 8, which in the arrangement shown, takes the form of an eye; this hole or eye being placed approximately on a continuation of the longitudinal axis of the bent portion, 5, of the tube. If the prong 2 be left straight it will narrow the passage between the prongs at the points and I therefore prefer to bend the prong 2, as indicated at 2^a, away from the other prong and paralleling the bend 5 in the latter; thus maintaining a substantial uniform spacing between the prongs throughout their length.

The locking device consists of a long thin spring wire, 9, having at one end a suitable head, 10, and being preferably pointed at its other end. The wire is of such a length that when it is thrust down into the passageway as far as the head thereon will permit it to go, the pointed end will be deflected laterally by the bend 5 and be directed through the outlet end of the passage and thence into the hole or eye in the opposite prong. Where the hole extends entirely through the prong, as shown, so as to form an eye, it permits the pointed end to

extend far enough through the prong 2 to insure that the short bridging piece between the two prongs cannot bend sufficiently to withdraw the pointed end from the hole and 5 thus release the interlock, through any pull which may come upon the pin in actual use, even though the locking wire be made thin and light.

It will be seen that there is no permanent 10 connection between the pin and the locking wire, the intention being that the wire shall be pulled completely out of the pin before the latter is placed in the hair. The pin is then thrust into the hole, 6, forming the inner 15 let end of the passage in the prong 1 and, as it is pushed inwardly, places itself in the position illustrated in full lines in Fig. 1, thus forming a tie or clamp around substantially the entire mass of hair which may 20 lie between the prongs of the pin. My improved construction permits the wire to be made light and flexible so that it may be easily pushed in or drawn out, the resiliency thereof, which tends to straighten the wire 25 at the upper angle of the bend, serving to press the wire against the walls of the tube forcefully enough to cause the wire to be held in place by friction. If desired, the lower end of the wire may be given an initial 30 set at an angle or along a curvature less than that which it must assume when in position in the pin, namely as indicated at 11 in Fig. 3, so that if the wire is properly held when inserted in the pin, it will have a natural 35 tendency to enter the bend in the tube when it reaches the latter.

While I have illustrated and described with particularity only a single preferred form of my invention, I do not desire to be limited to the exact structural details thus 40 illustrated and described; but intend to cover all forms and arrangements which come within the terms of the definitions of my invention constituting the appended 45 claims. I wish it to be further understood that my invention is not limited to hair pins although I have, for the sake of brevity, limited the detailed description to the hair pin illustrated; but my invention is applicable to hair fasteners of any kind in 50 which there are two prongs adjacent to each other.

I claim:

1. A hair fastener having two prongs arranged side by side and connected together at their bases, one of said prongs having an open ended passage extending lengthwise through the same from the base to a point on the inner side near the free end of 55 the prong, the other prong having near the free end thereof an opening facing the adjacent open end of said passage, and a light resilient wire long enough to extend through said passage and across the space between the prongs and into said opening.

2. A hair fastener having two prongs arranged side by side and connected together at their bases, one of said prongs having an open ended passage extending lengthwise through the same from the base to a point 70 on the inner side near the free end of the prong, the other prong having near the free end thereof an opening facing the adjacent open end of said passage, and a light resilient wire long enough to extend through 75 said passage and across the space between the prongs and into said opening, said wire having on one end a head adapted to limit the entrance of the wire into said passage and constitute a finger piece by means of 80 which the wire may be withdrawn from said passage.

3. A hair fastener having two prongs arranged side by side and connected together at their bases, one of said prongs having near the free end an inward lateral bend, there being in the bent prong an open ended 85 passage extending from the base lengthwise through the prong and through the offset or bend therein, the other prong having 90 therein an opening lying approximately in a continuation of a line passing lengthwise of said offset or bend; and a light resilient wire long enough to extend through said passage, across the space between the prongs, 95 and into said opening.

4. A hair fastener having two prongs arranged side by side and connected together at their bases, one of said prongs having near the free end an inward lateral bend, 100 there being in the bent prong an open ended passage extending from the base lengthwise through the prong and through the offset or bend therein, the other prong having 105 therein an eye lying approximately in a continuation of a line passing lengthwise of said offset or bend; and a light resilient wire long enough to extend through said passage, across the space between the prongs and through said eye.

5. A hair fastener having two prongs arranged side by side and connected together at their bases, one of said prongs having near the free end an inward lateral bend, there being in the bent prong an open ended 115 passage extending from the base lengthwise through the prong and through the offset or bend therein, the other prong having therein an opening lying approximately in a continuation of a line passing lengthwise 120 of said offset or bend; and a light resilient wire long enough to extend through said passage, across the space between the prongs, and into said opening, said wire having on one end a head adapted to limit the entrance of the wire into said passage and form a finger piece by means of which the wire 125 may be withdrawn from said passage.

6. A hair fastener having two prongs arranged side by side and connected together 130

at their bases, both prongs being bent laterally in the same direction near their free ends, the bend in one prong being directed toward the second prong, there being in the first prong an open-ended passage extending from the base lengthwise therethrough and through the bend therein, the second prong having therein an opening lying approximately in a continuation of a line pass-

ing lengthwise of the bend in the first 10 prong; and a resilient wire long enough to extend through said passage, across the space between the prongs, and into said opening.

In testimony whereof, I sign this specification.

ROY C. JONES.
